(57) **CLAIM**

The ornamental design for a multi-bottle container system, as shown and described.

DESCRIPTION

FIG. 1 is a front view of the multi-bottle container system of the present invention showing our new design;
 FIG. 2 is a side view thereof;
 FIG. 3 is a side view thereof;
 FIG. 4 is a rear view thereof;
 FIG. 5 is a top plan view thereof; and,
 FIG. 6 is a bottom plan view thereof.
